PENCIL

Filed Oct. 17, 1933

Inventor
Benjamin Hastings

UNITED STATES PATENT OFFICE

1,997,363

PENCIL

Benjamin Hastings, Brentwood, Md.

Application October 17, 1933, Serial No. 694,001

8 Claims. (Cl. 120—9)

My invention relates to improvements in pencils; and the objects of my improvement are, first, to prevent breaking of the leads; second, to provide a cantilever support for the protruding portion of the lead, which support shall not obscure the end of the lead from the operator's eye; third, to provide a cantilever support for the protruding portion of the lead, and means for rotating the lead and said support in relation to each other; fourth, to provide a refillable pencil that will permit the use of smaller sized leads than is at present practicable.

Fig. 1 is an elevation of the pencil.

Fig. 2 is an end view of the same.

Fig. 3 is an enlarged sectional view of that type in which the point of the pencil is integral with the barrel of same.

Fig. 4 is an end view of Figure 3, showing how a plane X—Y, tangent to the relieved portion of the point D, intersects the lead B.

These objects I attain by the devices shown in the drawing, in which, "A" is a pencil of the standard refillable type, with the lead "B" protruding from "A", "C" is an attachment, rotatable about "A", with a cantilever "D" extending beyond the bore of "A", and in close contact with "B" along its upper protruding surface. The cantilever "D" preferably has a greater dimension in the direction perpendicular to the lead, than the dimension of "D" cross-ways of the lead, so as to give rigidity in a radial plane and also an unobstructed view of the end of the lead. This form will also give a better grip for rotating the relative position of "B" and "D" to each other. The lower edge of "D" is grooved to provide lateral as well as vertical support for the lead "B" where it protrudes from "A".

"D" and "B" are rotatable in relation to each other, so that when the end of "B" has become worn, their relative positions may be changed, in order to allow "B" to be used on a fresh portion of the end of "B".

As shown "C" is detachably connected to "A"; but obviously may be made an integral part of

"A"; in which case "B" would need to be made rotatable within "A" by means not shown here.

My claims are—

1. A pencil wherein the point for supporting the lead for writing is cut away along one side at the outward end.

2. A pencil with a relieved point, for supporting the lead, the relieved part of said point adapted to be brought adjacent to the surface to be written upon.

3. A means of support for the lead of a pencil which in its operative position has said means cut away on the operating side of the lead.

4. A support for the lead of a pencil, adapted to hold the lead rigidly in line with the bore of the pencil, said support projecting beyond the barrel of the pencil, and having a relieved portion, operatively adjacent to the surface to be inscribed, whereby the lead may be brought into writing contact with said surface, without having to extend the lead beyond the outward end of said support.

5. A cantilever support for the lead of a pencil, at its outer end, which firmly supports the lead on one only of the four cardinal radial directions.

6. A mechanical pencil with a support for the lead at its outer end, which support surrounds the lead approximately two-thirds of the lead's perimeter, leaving the uninclosed side of the lead adapted to be brought into making contact with the surface to be marked.

7. A refill pencil with a support for the lead at its outer end, which supports the lead firmly in three only of the four cardinal radial directions, the support being cut away on the fourth side to such an extent, that the lead is exposed on this side, enough to make writing contact against a plane surface, when said side is brought adjacent to said surface.

8. A pencil with a support for the lead at its outer end, said support being cut away on the side to such an extent, that a plane, contacting the outer surface of the support at the cut-away part, will intersect that portion of the lead radially adjacent to the cut-away part.
